EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CUSHION.

No. 894,812.

Specification of Letters Patent.

Patented Aug. 4, 1908.

Application filed July 5, 1907. Serial No. 382,133.

To all whom it may concern:

Be it known that I, EDWARD G. BUDD, a citizen of the United States, residing at Philadelphia, in the county of Philadelphia and State of Pennsylvania, have invented 5 certain new and useful Improvements in Cushions, (Case A,) of which the following is a specification.

This invention relates to cushions especially adapted for use in seats of the type employed in railway cars. The invention is directed particularly to the provision of a cushion which may be used as a head-rest in a seat-back employed in sleeping-cars, such 15 head-rests being positioned above the back-cushions of the seats and adapted to be turned on an axis and held in an elevated position when the cushions of two adjacent seats are arranged to form a bed.

20 The object of the invention is to effect certain improvements in the construction of a cushion, to the end that a cushion is produced which is constructed largely of metal and is, therefore, practically fireproof, which 25 possesses ample strength and can be manufactured at comparatively low cost and which is particularly adapted for use as a head-rest.

30 The preferred embodiment of the invention is illustrated in the accompanying drawings, in which

Figure 1 is a top view of the cushion broken away and sectioned in part; Fig. 2 is an end view of the frame for the cushion; 35 Fig. 3 is a transverse section on line 3—3 of Fig. 1; and Fig. 4 is a detail view in section on line 4—4 of Fig. 1.

Referring to these drawings, the cushion is of rectangular form and its frame consists 40 of four metallic frame-members which are secured together at their ends. Each of the side-members 1, 1, and end-members 2, 2, of the cushion-frame consists of a strip of sheet-metal pressed to an angular cross-section as shown in Figs. 3 and 4, to provide a body portion 3 lying in the general plane of the frame and an integral flange 4 at the outer edge of the member turned downwardly of the cushion. Secured to the under side of 45 each of the frame-members, adjacent to the flange 4 thereon, is a strip 5 of wood, paper or similar material, to which the covering material of the cushion may be secured by tacks. The lower side-member 1 may be 50 secured at its ends to the ends of the end-

members 2 in any suitable manner; for this purpose, I have shown corner-boxes 6 of pressed sheet-metal, each having a downwardly-turned flange 7 corresponding to the flanges 4 on the frame-members, which is curved at the corner as shown in Fig. 1. The ends of the side and end members to be secured together are cut at an incline and each is secured to the corner-box 6 by means of rivets 8, the box 6 lying under the body 60 portions 3 of the two frame-members. The extreme ends of the two frame-members are cut away, so that the covering material of the cushion will lie against the corner-box 6 and the completed cushion will thus be provided with rounded corners at the lower edge. 65

At the upper corners of the cushion, bearing-pieces are provided adapted to coact with suitable bearings on the frame of the seat, so that the head-rest may be turned in these bearings to carry it from a position in which it lies in substantially the same plane as the back-cushion of the seat to a position in which it is inclined upwardly to carry it out of the way of an occupant of the bed and to form a shelf. I, therefore, provide the frame of the cushion with suitable supporting members to which detachable bearing-pieces may be secured, and I utilize 70 these supporting members both to form 75 corner-boxes for securing the ends of the frame-members together and to determine the shape of the covering material of the cushion. The supporting members are indicated at 9 and consist of castings each having a wall 10 lying in the general plane of the cushion-frame and two integral walls 11 and 12 lying perpendicular thereto and to each other. The wall 10 of each of the supporting 80 members has an integral extension 13, to which the end of the end-member 2 of the cushion-frame is secured by rivets. The end 85 of the side-member 1 is also similarly secured to the wall 10 of the supporting member. The wall 12 of the supporting member is also provided with an integral extension 14 extending alongside the flange 4 on the side-member 1 of the frame and riveted thereto. The wall 11 is provided with an integral ex- 90

95 tension 15 for the purpose hereinafter described. The members 9 thus serve to secure the upper side-member 1 to the end-members 2 of the cushion-frame and hold them firmly in proper relative positions. 100 105 110

The wall 11 of the supporting member has a shallow depression formed therein, into which the base of a bearing-member 16 may be drawn, this bearing-member being positioned after the covering material of the cushion has been applied thereto, as will be hereinafter described.

Secured to each of the end-members 2 of the cushion-frame is an end form-piece 17, consisting of sheet-metal pressed to the desired form, preferably that indicated in Fig. 4. From this figure, it will be seen that the piece 17 has an integral flange 18 which is secured by suitable rivets to the end-member of the cushion-frame, gussets 19 being provided to give greater strength and rigidity to the piece. At the upper edge of the end form-piece, an inwardly extending flange 20 is provided. In order to hold the end form-piece securely in position, it is also riveted to the extension 15 on the wall 11 of the supporting member. The wall 11 of the supporting member and form-piece 17 are of such size that the flange 20 continues the curve of the upper edge of wall 11 so that when the covering material of the cushion secured thereon, it is given the desired shape and held in the proper relation. Each of the members 9, therefore, serves as a support for a bearing-member 16, a corner-box for uniting two of the frame-members and a form-piece for determining the shape of the surface of the cushion. The members of the frame are thus united in such manner as to give great strength and the construction is such that the cost of manufacture is quite low.

Secured on the body portion 3 of each of the side-members 1 of the cushion-frame is a line of spiral springs 21, and the springs of each line support a flat sheet-metal plate 22 upon the upper ends thereof. A strip of coarse textile fabric 23 is laid over each of the sheet-metal strips 22 and its edges are carried down and secured to the tacking strip 5, so as to hold the springs 21 under tension. A sheet of fabric 24 is then laid over the cushion, and its edges carried down and tacked to the under sides of the strips 5. Upholstery material 25 is then laid over the fabric 24 and over this the outer covering 26 of plush or other suitable material. The edges of the covering 26 are also carried down and under the frame and are secured to the strips 5 by tacks. A sheet-metal pan 27 having an upwardly turned flange at its edge is then applied to the bottom of the cushion, its edges extending up over the edges of the outer covering 26 to protect the latter. The pan may be secured to the frame by screws entering the strips 5. This pan is of light sheet-metal, and it not only closes the bottom of the cushion so that the interior thereof does not show when the cushion is turned upwardly at night; but also it yields readily

if the head of the occupant of the bed strikes it.

After the outer covering 26 is applied to the cushion, the bearing-pieces 16 are secured to the supporting members 9. For this purpose, the walls 11 of the supporting members are provided with openings to receive screws 28, and these screws pass through countersunk openings in the bearing-pieces 16; as shown at the right of Fig. 1, and engage lugs 29 on the inner sides of the walls 11. By tightening up the screws 28, the bearing-pieces 16 and the portions of the covering 26 underlying them are drawn into the depressions in the walls 11 of the supporting members 9, so that the outer faces of the bearing-pieces 16 lie in substantially the same planes as the outer surface of the covering material at the ends of the cushion below the bearing-pieces.

Having now described my invention, what I claim as new therein and desire to secure by Letters Patent is as follows:—

1. In a cushion, a metallic frame, metallic supporting members at two of the corners thereof, a covering extending over the frame and secured at its edges thereto, and bearing-pieces secured to said supporting members and having projections thereon by which the cushion is supported, substantially as set forth.

2. In a cushion, a metallic frame consisting of frame-members secured together at their ends, metallic supporting members at two of the corners of the cushion each serving to unite two of said frame-members, a covering extending over said frame and secured at its edges thereto, and bearing-pieces secured to said supporting members and formed to provide supports for the cushion, substantially as set forth.

3. In a cushion, a frame consisting of sheet-metal frame-members secured together at their ends, metallic supporting members secured to the frame, a covering extending over the frame and said members and secured at its edges to the frame, and metallic bearing-pieces outside said covering secured to said supporting members and formed to provide supports for the cushion, substantially as set forth.

4. In a cushion, a metallic frame, supporting members secured thereto having depressions therein, a covering extending over the frame and said members and secured at its edges to said frame, and bearing-pieces secured to said supporting members outside said covering and entering said depressions, substantially as set forth.

5. In a cushion, a metallic frame consisting of sheet-metal frame-members secured together at their ends, two metallic supporting members each serving to unite the end of one frame-member to the end of another, a covering extending over the frame and said

members and secured at its edges to the frame, and metallic bearing-pieces outside said covering secured to said members and formed to provide supports for the cushion, 5 substantially as set forth.

6. In a cushion, a frame consisting of sheet-metal frame-members secured together at their ends, a tacking strip secured to each frame-member, metallic supporting members secured to the frame at opposite points thereon, a covering extending over the frame and said members and secured at its edges to said strips, and metallic bearing-pieces outside said covering secured to said supporting 10 members and formed to provide supports for the cushion, substantially as set forth.

7. In a cushion, a metallic frame consisting of sheet-metal frame-members secured together at their ends, a tacking strip secured to each frame-member, two metallic supporting members each serving to unite the end of one frame-member to the end of another and each having a depression therein, a covering extending over the frame and 20 said members and secured at its edges to said strips, and metallic bearing-pieces outside said covering secured to said supporting members and entering said depressions, substantially as set forth.

30 8. In a cushion, a frame consisting of sheet-metal frame-members secured together at their ends, two metallic supporting members secured to the frame at opposite points thereon and having walls extending upwardly therefrom, a covering extending over the frame and shaped by said walls and secured at its edges to said frame, and bearing-pieces outside said covering secured to said supporting members, substantially as set 35 forth.

40 9. In a cushion, a metallic frame, two metallic supporting members secured to the frame at opposite points thereon and having walls extending upwardly therefrom, sheet-metal form-pieces secured to the frame adjacent to said walls, a covering extending over the frame and shaped by said walls and form-pieces, its edges being secured to said frame, and bearing-pieces outside said covering secured 45 to said supporting members, substantially as set forth.

50 10. In a cushion, a frame consisting of sheet-metal frame-members secured together at their ends, two metallic supporting members secured to the frame at opposite points thereon, each having a wall extending upwardly from the frame and a depression in said wall, a covering extending over the frame and said members and shaped by said 55 walls, its edges being secured to said frame, and bearing-pieces outside said covering se-

cured to said walls and entering the depressions therein, substantially as set forth.

11. In a cushion, a frame consisting of sheet-metal frame-members secured together at their ends, tacking strips secured to said members, metallic supporting members each serving to unite the end of one of said frame-members to the end of another and each having a wall extending upwardly from the 60 frame and a depression in said wall, a covering extending over the frame and said supporting members and shaped by said walls, its edges being secured to said strips, and bearing-pieces outside said covering secured 65 to said walls and entering the depressions therein and having integral projections serving to support the cushion, substantially as set forth.

12. A cushion comprising a frame, spiral springs mounted thereon, a covering extending over said springs and secured at its edges to said frame, and a sheet-metal pan flanged at its edges covering the bottom of the cushion and secured at its edges to said 70 frame with said flange extending upwardly around the outer sides of the frame and overlying said covering, substantially as set forth.

13. A cushion comprising a frame formed of sheet-metal frame-members secured together at their ends, tacking strips secured to said frame-members, spiral springs mounted on said frame-members, a covering extending over said springs and yieldingly positioned thereby, its edges being carried 75 under said frame and secured to said strips, and a sheet-metal pan flanged at its edges covering the bottom of the cushion with said flanges overlying the covering, substantially 80 as set forth.

14. A cushion having a rectangular frame consisting of side and end members of pressed sheet-metal secured together at their ends, a line of spiral springs mounted on each of said side members, a sheet-metal strip 85 supported on each line of springs, two strips of fabric one overlying each of said sheet-metal strips and each of said strips of fabric having both its edges drawn down and secured to the side member of the frame on 90 which the sheet-metal strip covered thereby is supported by its line of springs, and a covering drawn over said strips and secured at 95 its edges to said frame, substantially as set forth.

115 This specification signed and witnessed this 22nd day of June, 1907.
